UNITED STATES PATENT OFFICE.

JOSEPH E. FLUKE, OF COVINGTON, KENTUCKY.

BORING-BAR.

SPECIFICATION forming part of Letters Patent No. 544,250, dated August 6, 1895.

Application filed March 28, 1895. Serial No. 543,557. (No model.)

To all whom it may concern:

Be it known that I, JOSEPH E. FLUKE, residing at Covington, in the county of Kenton and State of Kentucky, have invented certain new 5 and useful Improvements in Boring-Bars, of which the following is a specification.

My invention relates to an improvement in boring-bars for boring hubs or pulleys, car-wheels, and similar articles. It is also adapted 10 to be used with any ordinary lathe or drill. Its object is to provide positive, accurate, and convenient means for adjusting the cutting-bars to the required positions.

The features of my invention will be more 15 fully set forth in the description of the accompanying drawings, making a part of this specification, in which—

Figure 1 is a side elevation of my improved boring-bar. Fig. 2 is a section through the 20 same on line xx , Fig. 1. Fig. 3 is a section on line yy , Fig. 2. Fig. 4 is a perspective view of the traveling adjusting-head. Fig. 5 is a plan view of the screw-bar journal-plate. Fig. 25 6 is a perspective view of a sleeve for covering the boring-bar.

A represents the boring-bar, which is secured to the chuck of a lathe or drill-press by means of the tapered shank a .

BB' represent the cutters, which are seated 30 in a slot C in the boring-bar and project therefrom upon opposite sides of the bar, the inner or meeting ends of said cutters being beveled or inclined, as shown in Fig. 3. At right angles to slot C and intersecting a portion of it 35 is a second slot D, in which is mounted a traveling head E.

F represents a screw-threaded shaft tapping the head E and provided at one end with a wrench-seat e , by means of which the screw-shaft is revolved to feed the head E backward and forward. The screw-shaft F is journaled 40 in a plate G set in a recess in the side of the boring-bar, preferably in the following manner: The screw-shaft is provided with a head

1, connected to the body of the shaft by a 45 neck 2.

3 represents an opening through plate G for the passage of head 1.

4 represents a recess in which the head rests, and 5 a slot to receive the neck 2. 50

The traveling head E is provided with a wedge-shaped engaging-plate H, which engages the inner faces of the cutters, as seen in Fig. 3, and adjusts them radially to the desired position, where they are rigidly clamped 55 by set-screws II'.

By the means herein described I am enabled to secure an accurate, positive, and uniform adjustment of the cutters, which is not interfered with by chips or foreign matter 60 which may lodge in the slots or openings in the bar.

In order to effectually prevent the dust, grit, sand, &c., from entering the slot D and coming into contact with the working parts of 65 the adjusting devices, I provide sleeve K, which slips on over the boring-bar. Said sleeve K is provided with two recesses K for the reception of the cutters upon which the sleeve rests. 70

I claim—

1. In a boring-bar provided with intersecting slots C, D, the combination of the cutters B, B', seated in one of said slots, a traveling head E, seated in the remaining slot and carrying wedge shaped engaging plate interposed between the inner edges of the cutters, and a screw threaded shaft swiveled to the 75 boring-bar and tapping the traveling head, substantially as specified.

2. In a boring-bar employing radial cutters seated in a slot thereof, the combination with said cutters of the head E, the wedge H, the adjusting screw F tapping said head and swiveling in the bar whereby said wedge is 85 adjusted radially in its slot, substantially as specified.

3. In a boring-bar the cutter adjusting de-

vinces, consisting of the head E, the wedge H, and the screw F swiveled in plate G secured to the boring-bar, and having the wrench seat e upon the opposite side of the boring-bar, 5 substantially as specified.

4. In a boring-bar provided with intersecting slots, the combination with the cutters freely mounted in one of said slots, of a traveling head mounted in the other slot, and 10 carrying a wedge which enters between the cutters whereby they are adjusted longitudinally, a screw passing through the traveling

head whereby the latter is moved, a slotted plate secured to the boring-bar and serving as a journal for one end of said screw, and a 15 wrench seat formed upon the opposite end of the screw, substantially as described.

In testimony whereof I have hereunto set my hand.

JOSEPH E. FLUKE.
